UNITED STATES PATENT OFFICE.

WILLIAM AUTENRIETH, OF CINCINNATI, OHIO, AND JOSEPH M. THURSTON,
OF HAGERSTOWN, INDIANA.

SPECULUM.

SPECIFICATION forming part of Letters Patent No. 255,756, dated April 4, 1882.

Application filed December 12, 1881. (Model.)

To all whom it may concern:

Be it known that we, WILLIAM AUTENRIETH, of Cincinnati, Hamilton county, Ohio, and JOSEPH M. THURSTON, of Hagerstown, Wayne county, Indiana, have invented a new and useful Improvement in Speculums, of which the following is a specification.

Our invention relates chiefly to that class of speculums known as "rectum-speculums;" and the novelty consists in the construction and combination of the parts, as will be herewith set forth and more specifically claimed.

To more fully illustrate our invention, we will refer to the accompanying drawings, forming part of our application, in which—

Figure 1 is a view in elevation of our speculum, showing one of the fenestræ with the slide drawn over it, so as to close same. Fig. 2 differs only from the first in that the slide is drawn from the fenestræ, leaving it open. Fig. 3 is a longitudinal section of the speculum, and shows the interior of the speculum with one of the slides drawn over fenestræ. Fig. 4 is a view in cross-section taken through the line $y-y$, Fig. 3; and Fig. 5 is also a view in cross-section taken through the line $z-z$ of Fig. 3.

A is the body of the speculum. B are the fenestræ. C is a plug of metal, which in cross-section is round, used for the purpose of keeping the forward end of the slides D in position, and acting as a guide for said slides in their lateral movement in covering and uncovering the fenestræ. This plug is stationary within the speculum, made so either by casting it directly to the top part or by fastening it with a pin, as shown, and may be of any other convenient shape. It also performs another and very important function—viz., that of gently and painlessly forcing the walls of the rectum from the fenestræ when the speculum is being withdrawn. Each slide has a pin, p , which works in a slot, s , thus acting as a guide for the rear or lower portion of the slide in its lateral movement.

When it is desired to detach the slide from the speculum in order to obtain a more perfect view of the walls of the rectum, or for other reasons, it is moved so as to cover the fenestræ, when the pin p comes in line with the

notch n , and the slide can then be drawn out. It will be noticed that the rear portions of the slides are turned so as to conform with the flare of the tube, and their ends lipped and bent so as to embrace the end of the tube. Through these lips l are set-screws t , which serve to hold the slides firmly in position.

When it is desired to use this instrument the fenestræ are closed by the slides, and in this position it is inserted into the rectum. The gradual tapering of the exterior prevents any great pain being experienced by the person undergoing the operation. When the insertion is completed one or more of the slides, according to circumstances, are either moved back or drawn out, as is most desirable. After the fenestræ are opened the walls of the rectum pressing against the exterior of the speculum fall into the fenestræ. This enables the operator to discover the ailment and apply the necessary relief by the syringe, or whatever mode he deems best to adopt.

As before mentioned, when the slides are removed from the fenestræ the walls of the rectum press against the exterior of the tube and fall into the opening left by the said slides. Now, in withdrawing the speculum from the passage there is danger of the folds of the rectum which have fallen into the openings becoming bound, pinched, or injured. This, however, is prevented by the plug C, which, as the tube is withdrawn, comes in contact with the said walls, and gently and painlessly forces them out of the fenestræ, thereby saving much annoyance and trouble. Another feature of this plug is that it acts as an interior brace to the tube when it is made of thin material, and serves to insure strength and solidity.

The slides D, being attached to the interior of the instrument, prevent the wall of rectum from pain or injury while they are being moved or drawn out, as before mentioned.

We are aware that open-ended speculums having straight sides and with exterior slides have been before proposed, and do not claim such construction; but,

Having thus fully described our invention, we claim—

1. A rectum-speculum having its inserting end closed and rounded and having its outer end flaring, and provided with longitudinal openings or fenestræ, combined with interior 5 slides capable of both lateral and longitudinal adjustment to cover and uncover said openings, substantially as described.
2. In a rectum-speculum consisting of a tapering or straight tube with a smooth, rounded, 10 inserting end, and with longitudinal fenestræ or openings, the plug C, constructed as described and arranged within the tube at the upper end, whereby a guide for laterally-adjustable slides is obtained, and also a means 15 for the painless extraction of the speculum secured, substantially as described.
3. The slides D, having their rear portion turned so as to conform with the flare of the tube, and having guide-pins *p*, working in slots, together with the lips that embrace the end of 20 the tube, and set-screws *t*, as and for the purpose set forth.

WILLIAM AUTENRIETH.
J. M. THURSTON.
